CONCENTRATOR HAVING SLOPING RECIPROCATING TABLE WITH MOVABLE DECK

Adam Barnard Bouwer and Leslie Dorfman,
Johannesburg, Transvaal, Union of South AfricaApplication October 23, 1945, Serial No. 623,910
In the Union of South Africa July 20, 1945

1 Claim. (Cl. 209—433)

1

This invention relates to concentrators, for concentrating minerals and the like, more particularly to a concentrator having the form of a sloping table reciprocating longitudinally and down the length of which the material to be concentrated is washed, having also means whereby the flowing stream is rendered turbulent not only by the shaking, rocking or swinging of the table, but also by providing cells or pockets, having open tops and broken or slotted wall areas; said cells covering the area of the table top of the concentrator and providing a surface capable of separating and retaining concentrates.

The object of the invention is to provide the concentrator with a surface of concentrating cells, each cell formed by the combination of the openings in a fixed screen and the grooves in a travelling belt forming a top for the table and over which and in close parallel proximity to it the screen is fixed relatively to the belt.

The invention is illustrated diagrammatically in the accompanying drawings in which:

Fig. I is a side elevation of a concentrator according to this invention.

Fig. II is a side elevation of a small portion of the concentrating surface on an enlarged scale, showing the combined action of the wire mesh surmounting the grooved and travelling surface of the sloping floor of the concentrator.

Fig. III is a plan view on an enlarged scale of a small portion of the table top of the concentrator.

According to this invention the concentrator comprises a frame 1 carrying a sloping and shaking table 2 with a deck 3 in the form of an endless conveyor belt 4. The belt 4 is provided with a surface 5, preferably of rubber or like flexible material in which are formed grooves 6, furrows or the like, running transversely to the length of the belt 4 and preferably broken up into elongated pockets. The pockets or grooves 6, by which latter term they are hereinafter referred to, are suitably sized and shaped to retain concentrates under the concentrating action of the stream passing down the table 2, as hereinafter described. For instance the grooves may be of square cross section with vertical sides. The belt 4 is continuously moved up the slope against the downwardly flowing stream of material to be concentrated and is then passed back under the table top 3. It is washed free of concentrates and returned for a further journey through the active or concentrating zone. The

table 2 is provided with raised edges 7 between which the belt 4 moves.

Over the whole area of the table top 3 of the concentrator is fixed to the table 2 a perforated covering 8, preferably of stiff wire mesh having openings 9 in size equal approximately to the distance 10 between the centres of two or three of the grooves 6 on the moving belt 4. This perforated covering 8 should be fixed relative to the belt 4, to the frame 1 and just clear of said belt 4 so that the holes 9 in the mesh and the grooves 6 in the belt 4 form in combination a series of open topped and slotted sided cells 11 over the whole table top area.

15 The movement of the table top surface 3 is up the slope of the concentrating table and against the stream of material to be concentrated but care is taken that the new material fed to the table does not wash the concentrates from the grooves 6. For this reason the edge 20 of the feeding launder 12 is brought as close to the moving table top 3 as possible and the flow of the material onto the concentrator is made gentle. Baffles or other suitable means being used if necessary. In addition, just above or 25 under the feeding launder 12 the portion of the moving table top 3 may be fed with a stream 13 of clear or relatively clean liquid to ensure that the feed shall pass down the concentrator 30 and not be carried up under the feed launder 12.

For the efficient working of this concentrator it is necessary that the whole table 2 assembly comprising the edges 7, the perforated covering 8, and the portion of the belt 4 on the table top 35 3 should shake, reciprocate or vibrate. For this reason suitable mechanism 18 is provided, preferably combined with the endless belt 4 driving mechanism 14, for reciprocating the table 2. As shown, by way of illustration, mechanism 18 comprises an eccentric 19 and pitman 20 connected to the frame 1 at 21 while table 2 is hung in slings 22. 23 is a bevel gear driving an extensible shaft 24 connected to gears 14. The motor 25 provides the necessary power through suitable 40 belting.

Once the moving belt 4 has passed well under the feed launder 12 it is carried over a driving drum 15 and passes therefrom into a suitable washing tank 16 under the table 2. The belt 50 surface 5 is suitably washed free from the concentrates and the belt 4 returned to the carrier drum 17 at the lower end of the table 2 around which it passes for a fresh period of service as a table top 3.

55 The movement of the belt 4 up between the

edges 7 of the table 2 is preferably continuous but the movement may be made step by step.

This invention provides a shaking, sloping table concentrator having a table top 3 formed by a belt 4 having grooves 6 which, in combination with the openings 9 in mesh 8 provide specially shaped cells 11 and having means by which a part of the concentrating surface is made to travel continuously up the concentrating table 2, then be removed from the concentrating zone for washing, and reconditioning, and afterwards be returned to the lower end of the table 2 for a further period of service.

The grooves 6 in the surface of the belt 4 are, as stated above, preferably in the form of elongated pockets 7. By thus making the grooves 6 short in length they are more readily kept in proper shape. They are more rigid and this is important since any serious distortion is liable to displace concentrates which have settled at the bottom of the cells 11.

The form of the cells 11 making up the surface of this concentrator is important. The liquid in pouring in and out of each cell is made to "boil." Its surface is broken and, for example, no leaf gold is floated. The concentrates tend to sink in each cell as they are washed free and thereafter sink into the grooves 6 in the moving belt 4 and are thereby carried clear of the concentrating zone. In other words this invention provides a concentrator having the general form of a sluice box, the capacity and efficiency of a riffled strake, while at the same time the concentrating action is continuous and the concentrator can be kept at full capacity all the time.

There is no necessity during the concentrating operation for stoppages for cleaning-up, redress-

ing or for the renewal of corduroy or other cloths.

What we claim as new and desire to secure by Letters Patent is:

5 In a concentrator having a long table sloping longitudinally with means for oscillating the table in a longitudinal direction, feeding means at the top of the table for passing the material to be concentrated down the length of the table 10 and a surface for the table consisting of cells with open tops, slotted walls and retaining pockets, said cells comprising a belt moving upwardly against the passage of the material passing down the table, grooves in the surface of the belt, an open meshed screen fixed relatively to the moving belt and in close parallel association with the same, said grooves and the mesh of the screen combining to form concentrating pockets.
